UNITED STATES PATENT OFFICE.

ERNEST E. MALLORY, OF WEST UNITY, OHIO.

UMBRELLA.

SPECIFICATION forming part of Letters Patent No. 612,253, dated October 11, 1898.

Application filed November 19, 1897. Serial No. 659,199. (No model.)

To all whom it may concern:

Be it known that I, ERNEST E. MALLORY, a citizen of the United States, residing at West Unity, in the county of Williams and State 5 of Ohio, have invented certain new and useful Improvements in Umbrellas; and I do hereby declare the following to be a full, clear, and exact description of the invention, such as will enable others skilled in the art to 10 which it appertains to make and use the same.

My invention relates to improvements in umbrellas, more especially in what may be termed "short-folding" umbrellas.

Desiderata, particularly in this class of umbrellas, are to provide, among other things, for dispensing with the ordinary runner-stop as heretofore applied to the staff or stick for limiting the upward movement of the runner when the umbrella is long-folded. Said form 15 of stop is objectionable, not capable of use in short-folding the umbrella, in that said stop or catch is fixed and would therefore interfere with the running of the runner clear to the crown or notch, as required in the latter 20 form of disposing the umbrella. In my invention provision is made for limiting the upward movement of the runner when the umbrella is long-folded, which is also equally adapted for use in connection with the umbrella when short-folded.

Further objects of my improvements are to provide for the ready detachability of the handle, also that of the staff or stick, and the convenient attachment and removal of the 25 cap for the centering portion at the tip above the notch or crown, also conveniently clasping the umbrella-cover when folded.

To these ends my invention consists, primarily, of a retractile and automatically-projected dog or stop arranged in the staff or stick convenient of actuation when its retraction is required to permit the runner to pass the same, as in short-folding the umbrella; second, of means to retain said stop or dog retracted any considerable length of time, as in short-folding the umbrella for packing or transportation; third, of an end tube or flask adapted to be readily connected and disconnected to and from the staff or 40 stick adapted to permit of the ready application thereto of a handle or cap equally read-

ily detachable therefrom, and, finally, of means for conveniently and readily clasping the cover, all substantially as hereinafter more fully disclosed, and specifically pointed 55 out in the claims.

The scope of the invention extends to a retractile and automatically-projected stop or dog to engage the runner in its upward movement adapted to be held retracted under the 60 action of an axially-shiftable sleeve; also, to an end tube or flask adapted to be held detachably to the staff or stick and to serve as a closure for a clasping spring or ribbon for the cover and provided with spring-studs 65 adapted to permit the engaging therewith of a handle-piece; also, to a center cap-piece adapted to be readily secured in place and removable when desired.

In the accompanying drawings, illustrating the preferred form of carrying out my invention, Figure 1 is a side view of the umbrella long-folded with the spring tape or ribbon compactly clasping the cover. Fig. 2 is a sectional view showing the umbrella 70 short-folded and the runner-stop retracted under the axially-shiftable sleeve. Fig. 3 is a detached view of the staff or stick, showing the runner-stop as used when the umbrella is long-folded; and Fig. 4 shows the same 75 with the handle-piece detached and relatively disposed thereto. Fig. 5 is a sectional view of the handle-piece and end tube and a portion of the staff or stick, the other portion being broken away. Fig. 6 is a cross-section, 80 taken through said end tube, contiguously to and more fully disclosing the coiled spring ribbon or band. Fig. 7 is an enlarged detailed sectional view showing more fully the 85 tip and its adjunctive parts.

A refers to the staff or stick, B to the tip, C to the ribs, D to the stretchers, E to the cover, and F to the runners, the general features of an umbrella, all of which, except in the particulars hereinafter pointed out, are 90 substantially the same in construction as the corresponding parts shown and described in my concurrent application, Serial No. 659,198, filed of even date herewith.

The staff A proper is in several sections a 100 a' a'', the folding sections a' a'' being connected by the usual articulated link a'', inclosed by

a sliding sleeve a^4 , when the two sections are held inflexibly in alinement, said sleeve adapted to be slid from over said link when the staff is to be folded, as in short-folding 5 the umbrella. The remaining section a^2 of the staff or stick is in tubular form, preferably tapering, as at a^5 , a short portion of its length, and from there contracted diametrically, as at a^6 , to one end, that end connecting 10 with the section a' . This reduced end portion a^6 is sleeved upon the section a' and detachably connected thereto by compressible spring-catches a^7 , seated in said section a' and adapted to be snapped into an aperture a^8 in 15 said reduced end portion a^6 . The staff or stick has its upper end adapted to be detachably connected to the tip B, the connection being effected substantially as in my application aforesaid—i. e., the tip proper having 20 bayonet-like opposite or coincident slots a^9 and a sleeve b , adapted to be turned or movable upon said tip, and having corresponding slots b' , and the staff having a transverse pin a^{10} through it, with projecting ends engaging 25 said bayonet-like slots. When the slots b' a^9 are brought into coincidence by properly turning the tip, say slightly to the left, the staff can be pulled out of the tip-socket and detached from the tip.

30 The tip has slipped snugly down around it an apertured conical piece c , forming a cap or protector for the centering portion of the umbrella-cover to shed the water and protect the cover at that point. The cap c has upon 35 its inner flared circumference or portion a mutilated or broken circular flange portion c' , adapted to engage with a lateral stud or projection c^2 on the lower section of tip, and said tip and cap become interlocked.

40 The upper section B' of the tip is preferably let into the tubular lower section and adapted to be locked or fastened therein in like fashion as the staff is locked into said tip, a like pin and bayonet-shaped slots forming 45 the means of connection.

G is the runner-stop, comprising, preferably, the dog d , arranged and pivoted in a slot in the upper part of the staff, with its upper laterally projecting or offset end d' normally 50 standing out from the staff to intercept or limit the upward movement of the runner beyond that point in opening the umbrella when long-folded for use. The dog d has its inner or lower end pivoted or connected to 55 the upper end of a spring finger-piece d^2 , arranged in a diagonal extension of the aforesaid slot, with its lower end secured in the lower end of said slot extension, thus bringing said finger-piece to the opposite side of 60 the staff and adapting it, as is obvious, for engagement with the lower end or edge of the runner to retain it in position as against downward movement. This provides for the convenient actuation of the dog, and so that 65 when the pressure is exerted upon said finger-piece toward the staff while the hand is grasp-

ing the latter the projecting or offset end of the dog will be retracted as necessary in short-folding the umbrella. The spring finger-piece d^2 also, it will be seen, serves as a stop 70 when the umbrella is opened for the runner against downward movement.

H is a sleeve arranged on the staff or stick with a longitudinal slot e therein, through which the spring finger-piece protrudes. Said sleeve has also a short transverse slot e' therein, near its lower end, receiving a projection e^2 from the staff—in the present instance, a screw—to permit the sleeve to be 75 axially moved or turned sufficiently to cover 80 said spring finger-piece as the latter is pressed into its slot in the staff. The sleeve will thus hold the finger-piece and the finger-piece the previously-projecting or stop end of the dog retracted without further interference of 85 the hand until the sleeve is shifted back from over said finger-piece, again allowing said stop end of the dog to be automatically projected by the spring action of the finger-piece. The runner can now be run along the 90 staff unobstructed clear to the notch or crown, as required in short-folding the umbrella, as above intimated.

The runner F of the approved construction shown, described, and claimed in my above-referred-to application comprises, among other features, principally the series of radial spaced-apart arms f , fixed to the runner proper on the staff, the spring-fingers f' , connected to said arms upon opposite sides 100 thereof and to the stretchers D, and the sliding runner-section F', adapted to engage and throw said spring-fingers outward from the staff, this being effected when said runner-section is moved upward. By the opposite 105 movement of said runner-section said spring-fingers are permitted to more or less move inward toward the staff to relatively shorten the stretchers as needed in short-folding the 110 umbrella.

The runner-section may be itself held from any possible downward displacement by the use of pivoted clasps g , applied to opposite arms ff' of the runner proper, with their upper ends curved inward toward the latter and 115 having below said ends recesses adapted to receive said runner-section.

I is a form of strap for clasping the parts of the umbrella when short-folded, consisting in this example of a spring or steel ribbon 120 arranged or housed in the end section a^2 of the staff or stick after the fashion of the reeled steel measuring-tape, with its free end readily accessible and adapted to be drawn out through an opening or slot h in said staff 125 end section by the hand. This end of the ribbon or strap I has an inturned or hooked portion i , adapted to be engaged or caught upon a cross-bar i' in one end of the opening or slot h in the staff end section a^2 . The 130 clasping strap or ribbon I is readily drawn or uncoiled out of its housing in said staff

end section a^2 by pulling on said ribbon and is automatically rewound or coiled therein when released out of the way.

The interchangeable cap K and handle or 5 handpiece L are readily slipped upon the lower end of the staff-section a^2 and snapped fast thereon by opposite spring-studs k, spring-seated or cushioned in said staff-section and projecting therefrom to engage or 10 snap into coincident apertures k' in said handle-piece or cap.

The many advantages of my invention have been made apparent from the above. Among them it may be necessary to just refer here 15 only to the following: the ready adaptation of the umbrella for short-folding as well as long-folding, convenience and facility of handling, the ready dismembering of the parts to provide for compact folding or packing 20 thereof, as well as the easy repairing thereof, and also the ready clasping of the umbrella when folded.

It will be understood that I do not restrict myself to the details of the construction and 25 arrangement of the parts herein shown and described, as they may be readily changed or modified without departing from the spirit or principles of my invention and the same remain intact.

30 Having thus fully described my invention, what I claim, and desire to secure by Letters Patent, is—

1. In an umbrella, the combination, with the staff having a recess therein, and a runner, of a retractile, and projectile, diagonally-arranged stop located in said recess, 35 with its upper end and finger-piece projecting

from opposite sides of said staff and adapted to engage the upper and lower ends of said runner, substantially as set forth. 40

2. In an umbrella, the combination, with the staff and runner, of an axially-movable longitudinally-slotted sleeve, and a retractile and projectile dog or stop, with its detent projecting from one side of said staff or 45 stick and having a diagonal finger-piece extension adapted to project through said sleeve, and to be held retracted thereby, substantially as set forth.

3. In an umbrella, the combination with a 50 staff having a recess therein, and a runner, of the retractile and projectile dog or stop arranged in said recess, with its upper end and finger-piece projecting from opposite sides of said staff and adapted to engage the 55 upper and lower ends of said runner, respectively, and the sleeve having axial movement on said staff and a longitudinal slot, to provide for the retraction and projection of said dog or stop, respectively, substantially as 60 specified.

4. In an umbrella, the combination with the tip having a lateral pin or projection at its base, of the conical shield or cap adapted to be slipped upon said tip and having upon 65 its inner flared portion a mutilated circular flange adapted to engage said pin or projection, substantially as specified.

In testimony whereof I affix my signature in presence of two witnesses.
